UNITED STATES PATENT OFFICE.

HERBERT WILLIAM BENNETT, OF SOUTH HADLEY, MASSACHUSETTS.

DESIGN FOR A JARDINIÈRE.

51,626.

Specification for Design.

Patented Dec. 25, 1917.

Application filed May 1, 1917. Serial No. 165,794. Term of patent 8½ years.

To all whom it may concern:

Be it known that I, HERBERT W. BENNETT, a citizen of the United States, residing at South Hadley, in the county of Hampshire and State of Massachusetts, have invented a new, original, and ornamental Design for Jardinières, of which the following is a specification, reference being had to the accompanying drawing, forming a part thereof.

The figure is a perspective view of a jardinière, showing my new design.

I claim:

The ornamental design for a jardinière, as shown.

HERBERT WILLIAM BENNETT.

Witnesses:

HARRY A. BATES,
DANIEL J. O'CONNELL.
